UNITED STATES PATENT OFFICE.

PAUL W. SCHIEMAN, OF ROCKVILLE CENTER, NEW YORK, ASSIGNOR TO THE A. DEWES COMPANY, OF NEW YORK, N. Y., A CORPORATION OF NEW YORK.

JACK.

1,329,098.

Specification of Letters Patent.

Patented Jan. 27, 1920.

Application filed May 24, 1917. Serial No. 170,589.

To all whom it may concern:

Be it known that I, PAUL W. SCHIEMAN, a citizen of the United States, and a resident of Rockville Center, in the county of 5 Nassau and State of New York, have invented certain new and useful Improvements in Jacks, of which the following is a specification.

The invention relates to a new manually 10 operative jack adapted for use in connection with motor vehicles, as well as being capable of efficient use in lifting or jacking-up other vehicles and apparatus.

The jack of my invention comprises a 15 general casing, which will preferably be made of stamped metal, a vertically movable lifting-bar mounted in said casing, and a pivoted manually operative handle for effecting the movement of said lifting-bar, 20 together with certain more particularly novel features residing in a new construction and arrangement of operative parts connected and coöperating with the lifting pawls or dogs which alternately engage said 25 lifting-bar during the operation of said handle, means for reversing the action of said pawls or dogs so as to secure the descent of the lifting-bar when it is desired to lower the load, means for conveniently releasing 30 both pawls or dogs from the lifting-bar when it may be desired to allow the said bar to drop to its lower position without the necessity of operating said handle, and an auxiliary low step or shoe which may be 35 employed for engaging the load when the same cannot conveniently be received by the main head on the upper end of the lifting-bar, said auxiliary low step or shoe having a novel construction and mounting 40 adapting it for various adjustments and to successfully sustain the load which may be imposed upon it.

The invention will be fully understood 45 from the detailed description hereinafter presented, reference being had to the accompanying drawings, in which:

Figure 1 is a vertical section through a jack constructed in accordance with and embodying the invention, the parts of the 50 mechanism of the jack being shown in the position they occupy when the operating lever handle is in its upper position and the vertically movable lifting-bar has been started in upward motion, the section being on the dotted line 1—1 of Fig. 2;

Fig. 2 is a front elevation, partly in vertical section, of the same, the front of the main casing having been removed so as to expose the interior mechanism;

Fig. 3 is a view corresponding with Fig. 60 1, partly broken away, showing the relative relation of the various parts of the mechanism after the operating lever handle has been turned downwardly to nearly its lower position in the process of elevating 65 the lifting-bar;

Fig. 4 is a corresponding view showing the relative relation of the parts of the mechanism after the operating lever handle 70 has reached its lower position and the upper pawl or dog has passed into engagement with the lifting-bar;

Fig. 5 is a perspective view of the jack, with the lever handle partly broken away and in its lower position and the mechanism set for effecting, from said handle, the lowering of the lifting-bar, and the lateral lifting member or low step or shoe being shown at the side of the jack instead of at the rear thereof, as in Fig. 1; 75

Fig. 6 is a view corresponding with Fig. 1, partly broken away, showing the relative relation of the parts of the mechanism when the same are set for the lowering of the lifting-bar, the operating lever handle 85 being shown somewhat above its lower position;

Fig. 7 is a corresponding view of a portion of the same illustrating the relative relation of the parts of the mechanism when 90 the operating handle has reached a lower position than that illustrated in Fig. 6;

Fig. 8 is a vertical section through the auxiliary lateral lifting member and is presented to illustrate the manner of vertically 95 adjusting the step or shoe of the same;

Fig. 9 is a sectional view corresponding with Fig. 1, but illustrating the two dogs as nearly tripped from the lifting bar;

Fig. 10 is a transverse section through the 100 jack, taken on the dotted line 10—10 of Fig. 1, and

Figs. 11 and 12 are detached perspective views of two parts of the operative mechanism of the jack identified hereinafter. 105

In the drawings, 15 designates the general exterior casing of the jack whose two sides and back portion are preferably in one integral stamping of sheet metal and whose front portion comprises a lower section 16 110

and an upper removable section 17, more clearly shown in Fig. 5, which is fastened to the body of the general casing by screws 18 and by being interposed at its upper end 5 behind a lug 19 formed of the general casing and extending frontwardly of the lifting-bar 20. The general casing composed of the parts is secured at their lower edges to a base composed of a stamped metal exterior 10 portion 21 and a filling 22, which may be of wood. The lower edges of the casing are flanged under adjacent portions of the base member 21, as shown in Figs. 1, 6 and 9. The base portion of the jack may be variously modified, but I illustrate a base which is capable of being readily constructed and comprising a stamped up metal part or cap 21 and a wood filling 22. The back portion of the general casing 15 is made narrow, as at 23 (Fig. 10), to serve as a guide for the lifting-bar 20. At convenient points the opposite sides of the guide 23 are provided with inwardly extending pins 24 entering vertical grooves 25 in the opposite 20 sides of the lifting-bar 20 so as to aid in guiding said bar and retaining the same within the narrowed back portion of the casing 15. At the lower end of the lifting-bar 20 and secured thereto are laterally extending pins 26 which are within the aforesaid grooves 25 and directly below the aforesaid pins 24, and during the upward movement of the lifting bar the pins 26 finally reach the pins 24, which are rigid with the 30 casing 15 and at such time the pins 24 by their engagement with the pins 26 arrest the bar 20 on its upward movement, defining the limit of the upward movement of said bar. At the limit of its downward movement, the lifting bar 20 may extend into a recess 27 formed in the general base of the device.

The lifting-bar 20 is a strong metal bar which is rectangular in cross-section and has on its front face a series of rack teeth 28 adapted to the lower and upper pawls or dogs 29, 30, which alternately coöperate with the rack teeth 28 during the operation of the jack to either raise or lower the lifting-bar 20, although as hereinafter described, I have provided means by which both of said pawls may be released from the bar 20, so that said bar may descend by gravity. Upon the upper end of the bar 20 45 is provided a concave foot 31 adapted to receive the axle or other part of the object to be lifted and formed with a depending head or socket portion 32 which closely fits upon the upper end of the bar 20 and 50 may be detachably connected therewith by means of an ordinary set-screw 33. The head or socket 32 is, at one side, formed with laterally extending arms 34 between which is pivotally mounted a supplemental 55 bar 35 which extends downwardly along the

general casing 15 and at its lower end may swing against the same, so as to obtain support therefrom, as shown in Fig. 1. The socket in the head 32 is rectangular in cross-section and may be applied upon the bar 20 70 so that the supplemental bar 35 will extend downwardly at the rear of the general casing 15, as shown in Figs. 1 and 6, or at either side of said casing, as will be understood on reference to Fig. 5. The bar 35 75 is of T-shape in horizontal cross-section, thereby forming a web portion which is held by the pivot 36 between the arms 34 of the head or socket 32 and a head portion 37 affording flanges extending laterally 80 from said web portion and which portion 37 is formed in its outer face with a series of recesses 38. Upon the bar 35 is placed a vertically adjustable step or foot 39 comprising a horizontal member 40, a downwardly extending member 41 engaging the outer face of the bar 35, and inner and laterally extending members 42 which embrace the side edges of the head 37 and extend inwardly along the inner faces of 90 the flanges afforded by said head 37. The vertical portion 41 of the step or foot 39 is formed with a stud 43 adapted to enter any of the recesses or sockets 38 formed in the outer face of the bar 35. The step or 95 foot 39 is vertically adjustable on the bar 35, and in Fig. 8 I illustrate said step or foot in a tilted position releasing its stud 43 from one of the recesses or sockets 38 so that said step or foot may be slid either upwardly or downwardly on the bar 35 and have its stud 43 engaged with some other one of the sockets or recesses 38 for the purpose of varying the initial position of said step or foot 39. The jack is used under 100 varying conditions and sometimes the foot or shoe 31 may answer the requirements, but at other times the side supplemental step or foot 39 will become necessary, and in the construction presented the initial height 110 from the ground of said step or foot 39 may be varied to suit the conditions to be met with. When the step or foot 39 is tilted upwardly, as shown in Fig. 8, it may be slid upwardly or downwardly on the head 37 115 of the bar 35 and have its stud 43 introduced in any of the sockets or recesses 38 to secure the proper vertical adjustment of said step, said step when reaching the desired recess or socket 38 being turned into 120 its horizontal position so as to project the stud 43 into such recess or socket 38.

Among the novel features of the jack are the hinged bar 35 adapted to engage, at its lower portion, the general casing 15 and the 125 adjustable step or foot 39 mounted on said bar. It will be observed that by reason of the pivoting of the bar 35 a weight imposed on the step or foot 39 will exert its force against the general casing 15 as well as on 130

the pin or pivot 36, and that in consequence thereof such weight will not be likely to bend or break the lifting bar 20 or do other damage to the jack, and this is a result 5 which I deem to be of very great importance. The fact that the supplemental bar 35 and step or foot 39 may be disposed at the rear of the general casing 15 or at either side thereof, is also a matter of importance in 10 affording proper conveniences to the user of the jack. A weight imposed on the step or foot 39 is well supported, not only by the engagement of the stud 43 with one of the sockets or recesses 38, but also by the inner 15 wall of the vertical member 41 engaging the outer face of the head 37 of the bar 35 and the engagement of the flanges 42 at the inner end of said step or foot 39 with the inner faces of the vertical flanges afforded by said 20 head 37. The bar 35 is provided at opposite sides of its lower end with pins 44 which serve to prevent the step or foot 39 from slipping downwardly off from said bar. The bar 35 is prevented from having any 25 swiveling action around the bar 20, since said bar 20 is rectangular in cross-section and the socket in the head 32 corresponds in shape with and fits upon said bar 20.

The pawl or dog 30 is of substantial 30 width, as shown in Fig. 2, and is pivotally mounted on a transverse pin 45, which extends through the lower end of said dog or pawl and through the opposite sides of the general casing, and I may here state that the 35 opposite sides of the general casing are made of double thickness, as shown in Fig. 10, so as to afford, in a stamping, the requisite strength to withstand the uses to which the jack may be put. The double thickness 40 of the sides of the general casing of the jack also afford substantial bearings for the pin 45 and the other pins or the like to be referred to hereinafter. The upper end of the pawl or dog 30 is adapted to the teeth 45 of the lifting-bar 20, and adjacent to its upper end said dog or pawl 30 is formed on one side edge with an arm 46 which projects forwardly or toward the front of the jack and carries a small roller or pin 47 at the 50 front of a cam arm or plate 48 (Fig. 11) which is pivotally secured by a screw 49 to the upper front portion of a plate 50 (Fig. 12) which extends downwardly along the side of the pawl or dog 29 and is mounted at 55 its lower end upon the pivot pin 51 for the said dog or pawl 29. When the bar 20 is being lowered the upper cam shaped end of the plate 48 is adapted to ride against the roller 47 and pull the engaging end of the 60 pawl 30 from the rack bar 20 at the time the dog 29 engages said bar, and thereafter the plate 48 will turn with the dog or pawl 30 toward the bar 20 when it is desired that said dog or pawl shall engage said bar 20 65 and support the load. During the upward

movement of the lifting bar 20 the cam plate 48 has a nominal spring tension outwardly or toward the front by the downwardly extending member 52 of a coiled spring 53 which is held upon a transverse pin 70 54 and has its downwardly extending member or arm 52 confined behind a lip 55 formed on the forward edge of the plate 48. The spring 53 is of course stationary, except for its pivotal movement, whereas the plate 48 has a vertical reciprocating movement imparted to it during the operation of the jack, and when the plate 48 is moved upwardly, its upper cam shaped end 80 is caused to ride against the roller 47 and pull the dog or pawl 30 outwardly from the lifting bar 20, this taking place more especially during the descending movement of the lifting bar 20 and when the tension of 85 the spring 53 has been materially increased by the means, hereinafter described, provided to so set the mechanism that the bar 20 will descend when the lever handle is operated. The lower rearwardly projecting 90 portion of the plate 48 is formed with a somewhat triangularly-shaped slot or opening 56, and within this opening 56 projects a pin 57 which is rigid with the upper end of the lower pawl or dog 29. The opening 56 and pin 57 permit of the plate 48 having a pivotal movement with relation to the plate 50 and pawl or dog 29. The pin 51 upon which the lower dog or pawl 29 and plate 50 are secured does not extend through 100 the sides of the casing of the jack, but through the inner forked end of the handle-socket 58 which is pivotally mounted upon a pin 59 which extends through the sides of the general casing of the jack. The inner end 105 of the handle socket 58 serves as a crank for raising and lowering the dog or pawl 29 and parts connected therewith, and at its outer end said socket 58 is adapted to detachably receive a handle-bar 60, whereby the jack 110 may be operated, said handle bar and socket constituting a lever handle for actuating the operative parts of the jack.

The part I have termed a handle-socket 58, is a hand actuating lever and, preferably, instead of being made of considerable length said lever is formed with the usual socket, as shown, to receive the bar 60.

The dogs 29, 30 are normally pressed toward the lifting-bar 20 by means of a spring 120 60 which is mounted on a pin 61 (Fig. 2) and has a downwardly extending end 62 pressing against the dog or pawl 29 and an upwardly projecting end 63 pressing against the dog or pawl 30.

The lever handle is always given its ordinary oscillatory movement, whether it is desired that the lifting-bar 20 of the jack shall ascend or descend. In the position of the parts shown in Figs. 1, 2, 3 and 4, the 130

oscillatory motion of the lever handle will, through the action of the pawls or dogs 29, 30 effect a step-by-step upward movement of the lifting bar 20 and load supported thereon. I however provide means for so affecting the relation of the inner mechanism of the jack that during the oscillatory motion of the lever handle, the lifting bar may, by a step-by-step movement, descend, and these means reside mainly in a thumb-piece or reverse setting lever 64 pivotally secured to the inner side wall of the general casing by means of a screw or the like 65 and having on its disk-shaped inner end a laterally projecting pin 66 which normally is below an arm 67 of the spring 53 which acts against the plate 48. When the thumb-piece or lever 64 is turned upwardly or to the position shown in Figs. 1, 2, 3, 4 and 9, the pin 66 is carried downwardly from the arm 67 of the spring 53 and has no appreciable influence on said arm or spring, except to almost wholly relieve the spring of its tension, and at this time the operation of the lever handle and pawls or dogs 29, 30 will be to elevate the lifting-bar 20. When however the thumb piece or lever 64 is turned downwardly or to the position shown in Figs. 5, 6 and 7, the pin 66 will be carried upwardly against the arm 67 of the spring 53, and materially increase the tension of said spring so that its lower member 52 will act with positive force against the cam plate 48, and under this condition of the mechanism the lifting-bar will descend by a step-by-step movement on the operation of the lever handle.

The means for effecting the drop or descent by gravity of the lifting bar 20 comprise a downwardly extending arm 68 which is integral with the body of the lifting pawl 29, and a frame 70 which is formed of a bent metal rod having its lower end pivotally secured at 71 to a bracket 72 within the general casing 15. The frame 70 at its inner bent portion, which is of curved outline, rests against the arm 68 of the pawl 29, and the upper horizontal portion of the frame 70 projects through a hole 73 formed in the lower front portion 16 of the casing 15 and within the casing is provided with a cross-pin 74, which prevents the upper end of the frame 70 from passing unduly out through the hole 73. The frame 70 has a limited oscillatory movement on the pivot 71, and during the ordinary use of the jack the arm 68 acts against the frame 70 so that the latter will oscillate, but at such time said frame 70 performs no duty. The frame 70 is made use of only when the lifting bar 20 is to automatically drop, and at such time the frame 70 is caused to trip both of the pawls 29, 30 from said lifting bar. It is not necessary at any time that the lifting bar 20 be caused to drop, but it is thought to be

a saving in time on some occasions to, after the bar 20 has been worked downwardly by means of the lever handle until the load has been taken off of said bar, permit the bar to drop. When it may be desired that the bar 20, in my jack, drop automatically, I will withdraw the handle bar 60 from the socket 58 when said handle bar and socket have been turned down to their lower position, and then poke or push the end of the bar 60 against the exposed end of the frame 70, the result of which will be that the frame 70 will be forced inwardly against the arm 68 and effect the tilting outwardly of the pawls 29, 30 from the bar 20, leaving said bar unsupported and of course therefore permitting it to drop. When the handle lever is turned to its lower position the arm 68 presses the frame 70 to an outer position or substantially that in which it is shown in Fig. 1, and at this time the lifting bar is supported on the pawl or dog 30. When, by means of the bar 60, the upper end of the frame 70 is pushed inwardly to carry the bend of said frame against the arm 68, both pawls 29, 30 are tilted outwardly and the bar 20 is allowed to drop. The presence of the frame 70 in position to coöperate with the arm 68 and to be operated from a distance by the bar 60, is quite a convenience, because the exposed end of the frame 70 may be conveniently reached by the bar 60 from a distance and without any special hunting for the exposed end of said frame 70, which will always be directly below the socket 58 for the bar 60. The tripping of the dogs from the lifting bar 20, when the lever handle is in its lower position, may be performed by pressing the frame 70 inwardly, whether the thumb piece or setting lever 64 is turned upwardly or downwardly, but this tripping of the pawls from the bar 20 is usually performed when the thumb piece or setting lever 64 is turned downwardly, because the dropping of the bar 20 is not supposed to take place until said bar has been worked downwardly by the lever handle to such extent that the load has been relieved from its upper end. After the lifting bar has been allowed to drop, the setting lever 64 should be turned upwardly so that the jack may be in condition for use for elevating purposes, and therefore after the frame 70 has been pushed inwardly, as shown in Fig. 9, to trip both pawls from the lifting bar and said bar has been allowed to drop, the handle bar 60 may be used, at a reasonable distance from the jack, to turn the setting lever 64 to its upward position and then returned to the socket 58, thus leaving the jack in condition for further use if desired. In Fig. 9 I illustrate a condition in which the bar 60 has been used to push the frame 70 inwardly for the purpose of permitting

the bar 20 to drop and then employed for turning the setting lever 64 to its upward position, after which the handle bar 60 is shewn as having been returned to the 5 socket 58.

The operation of the jack will in many respects be understood from the foregoing description, but it is necessary that further explanation be made as to the mechanism 10 more directly coöperating with the pawls or dogs 29, 30.

When the lifting-bar 20 is to be elevated, the setting-lever 64 will be turned to its upper position, shown in Fig. 1, and this, as 15 hereinbefore explained, has the effect of leaving only a nominal tension on the spring 53 insufficient to modify the action of the spring 60 whose ends respectively press against the pawls or dogs 29, 30, the plate 20 48 thus being deprived, during the elevation of the bar 20, of any special utility. Upon the oscillatory motion of the lever handle, under the conditions just stated, the pawl or dog 29 becomes the lifting pawl or dog, 25 and the pawl 30 by engaging the lifting bar, serves to support said bar and the load thereon when the pawl or dog 29 recedes from a tooth of the lifting bar and moves downwardly to engage the next lower tooth there- 30 of. In the position of the parts shown in Fig. 1, the lever handle has been turned to its upper position and the dog 29 has entered a tooth of the lifting bar 20 and the dog 30 is ready to recede from the lifting 35 bar on the down-stroke of the lever handle or move to the position shown in Fig. 3. On the down-stroke of the lever handle, the dog 29 elevates the lifting-bar 20 and the dog 30 remains in readiness to again engage 40 said lifting-bar after the pawl 29 has performed its duty and is to be withdrawn from said bar, the pawl or dog 30 then taking the position shown in Fig. 1, as distinguished from that illustrated in Fig. 3. The dogs 45 or pawls 29, 30 act alternately and are pressed against the bar 20 by the spring 60. The release of the dog 30 from the rack-bar 20 takes place when the dog 29 has engaged a tooth of said bar and has been actuated to 50 elevate the bar 20, the dog 30 during this period riding out from the tooth of said bar it engaged so as to snap into position below the next lower tooth thereof preparatory to supporting the load when the pawl 55 29 has completed its upward stroke. On the up-stroke of the lever-handle, the pawl 30 supports the bar 20 and the load thereon and the pawl or dog 29 rides down the bar 20 to engage another tooth thereof.

60 When the lifting bar 20 is to be lowered, so as to lower the load imposed thereon, the setting-lever 64 will be turned to its lower position, shown in Figs. 5, 6 and 7, and this, as hereinbefore explained, has the effect of 65 causing the pin 66 at the inner end of said

lever to move outwardly against the arm 67 of the spring 53 and thereby increase the tension of said spring, through its arm 52, against the lip 55 of the plate 48. Upon the oscillatory motion of the lever-handle, under 70 the conditions just stated, the pawls or dogs 29, 30 are alternately acted upon to effect the lowering of the lifting bar 20 by a step by step movement. When the lever-handle is turned upwardly to lower the dog 29 and 75 plate 48 (and therewith the bar 20), the plate 48 turns outwardly on the pivot 49 due to the shape of the upper portion of said plate and the tension of the spring-arm 52 against the same, and at this time the dog 80 or pawl 30, under the action of the spring-arm 63 is moved against the lifting-bar 20 so that it may support the same when the dog or pawl 29 is freed from said bar by being turned outwardly therefrom on the 85 pivot 51, this turning-outwardly of the dog or pawl 29 being effected by the lowering on a downwardly and forwardly extending arc line of the pivot 51 and the upward and outward movement on an arc line of the 90 rearwardly projecting lower portion of the plate 48, whereby the wall of its opening 56 is caused to act against the pin 57, which is rigid with the pawl or dog 29, to draw said dog or pawl 29 forwardly from the bar 20 95 in opposition to any force the spring-arm 62 may exert. The joint action of the plate 48 and lever-handle near the end of the upward movement of said handle, has the effect, before the dog 30 is ready to leave the 100 lifting-bar, of substantially positioning the dog 29 to engage said bar as soon as the lever-handle is turned downwardly. Upon the downward movement of the lever handle the dog 29 first engages the lifting-bar 20 105 and elevates the same slightly so as to relieve the load from the dog or pawl 30, and thereupon the arm 52 of the spring 53 turns the plate 48 outwardly, and this acts against the roller or pin 47 connected with the dog 110 or pawl 30 and moves said pawl outwardly from the lifting bar, the dog or pawl 29 then supporting said bar and the load imposed thereon. Upon the succeeding upward movement of the lever-handle, the lifting- 115 bar, supported by the dog or pawl 29, is lowered one step and the dog or pawl 30 becomes positioned to engage the tooth 28 next above the one it had previously engaged so that it may support said bar on the 120 downward movement of the lever-handle or until the dog 29 has ascended a space equal to one space of the lifting bar and then moved inwardly to support said bar and move the same slightly in an upward direction so as to relieve the load from the pawl or dog 30 and permit said dog 30 to be retracted from the bar 20 by the plate 48 under the action of the spring-arm 52 against the lip 55. The oscillatory move- 125 130

ment of the handle-bar is continued with the pawls alternately engaging the lifting bar 20, each always one tooth above the tooth it had previously engaged, until the 5 load has been lowered sufficiently to relieve its strain from off the bar 20, and at that time the lifting bar 20 may be worked downwardly by the action of the lever-handle until it has reached its extreme lower position, 10 or, at such time, the operator may withdraw the bar 60 from the socket 58 and push the same against the exposed end of the frame 70, thereby driving said frame inwardly against the arm 68 of the dog 29 and 15 through said dog and plate 48 moving said dogs or pawls outwardly from the lifting bar, allowing said bar to automatically drop to its lowest position.

The setting-lever 64 and plates 48 and 20 50 are of special importance when it is desired to lower the lifting-bar by a step by step movement on the usual oscillatory movement being imparted to the lever-handle. During the upward movement of the lever 25 handle the dog or pawl 29 and plates 48 and 50 move downwardly, and due to the shape of the upper end of the plate 48 the arm 52 of the spring 53 is permitted, at this time, to turn the upper portion of said plate 48 30 outwardly or toward the front, and during the downward movement of the lever-handle the forwardly curved protuberance or cam edge of the plate 48 is caused, after the dog or pawl 29 has engaged and slightly lifted 35 the lifting-bar, to ride against the pin or roller 47 connected with the dog or pawl 30 and turn said pawl outwardly from the lifting bar. The plate 48 is a cam-plate because on its upward movement it acts as 40 a cam against the roller or pin 47 connected with the dog or pawl 30; and during the upward movement of the lever-handle the plate 48 is acted on by the spring 53 to move outwardly in a direction from the lifting 45 bar, but at this time said plate 48 has no effect on the dog or pawl 30 because its upper inwardly bent portion then rides idly against the aforesaid roller or pin 47. On the upward movement of the dog or pawl 50 29 the same operates through the pivot 49 and pin 57 to force the plate 48 upwardly so that its curved edge will ride inwardly against the pin 47 connected with the pawl 30 for finally retracting said dog or pawl 55 30 from the lifting bar, and on the downward movement of said dog or pawl 29 and plate 48, the plate 48 is turned outwardly by the spring-arm 52 and the upper arm 63 of the spring 60 is gradually freed to move 60 the pawl or dog 30 against the lifting-bar.

On the down-stroke of the lever-handle, the plate 48 becomes lifted and is turned inwardly toward the lifting-bar, and on the first portion of said stroke of the lever-handle the dog 29 is moved against the bar

20, and then on the continued downstroke of said lever-handle the dog 29 lifts the bar 20 so that the plate 48 may complete its movement and retract the dog 30, the bar 20 then being supported by the pawl or dog 70 29; and then on the upstroke of the lever-handle, the dog 29 descends with the bar 20 and load imposed thereon and carries with it the plate 48, which turns outwardly under the force of the spring-arm 52 and 75 finally permits the spring-arm 63 to restore the dog or pawl 30 into engagement with the lifting-bar 20 to support the same preparatory to the lever-arm being again turned downwardly to carry the dog 29 upwardly 80 to engage the next higher-up tooth of said bar and also to again effect the release of the pawl or dog 30 from the bar 20.

The operation just above outlined continues so long as the user of the jack 85 desires to lower the lifting bar by the oscillatory motion of the lever-handle.

What I claim as my invention and desire to secure by Letters Patent is:

1. A jack comprising a casing and base, 90 a vertical toothed bar mounted in said casing to support the load, an actuating hand lever pivotally mounted at its inner portion between the sides of said casing, a pawl having a pin on its side and pivotally mounted 95 on the inner end of said actuating lever and operable therefrom and adapted to engage said bar, and a second pawl pivotally mounted between said sides and adapted to engage said bar while the other or first pawl 100 is disengaged operatively therefrom, said second pawl having a projecting arm combined with a cam-plate pivotally mounted adjacent to the side of said first pawl and having an upper portion to engage said arm 105 and a lower angular portion containing an opening receiving said pin on said first pawl, and a spring engaging said cam-plate and acting to turn the upper portion of said plate outwardly against said arm of said 110 second pawl, said cam plate having an edge to ride against said arm when said plate is moved upwardly and withdraw said second pawl from said toothed bar and to recede from said arm when moved downwardly and 115 thereby permit said second pawl to engage said bar and support the load until the first pawl is again moved upwardly and has engaged said bar, whereby on the oscillatory movement of the actuating lever the lifting- 120 bar becomes lowered.

2. A jack comprising a casing and base, a vertical toothed bar mounted in said casing to support the load, an actuating hand lever pivotally mounted at its inner portion 125 between the sides of said casing, a pawl having a pin on its side and pivotally mounted on the inner end of said actuating lever and operable therefrom and adapted to engage said bar, and a second pawl pivotally 130

- mounted between said sides and adapted to engage said bar while the other or first pawl is disengaged operatively therefrom said second pawl having a projecting arm, combined with a cam-plate pivotally mounted adjacent to the side of said first pawl and having an upper portion to engage said arm and a lower angular portion containing an opening receiving said pin on said first pawl, a 5 spring engaging said cam-plate and acting to turn the upper portion of said plate outwardly against said arm of said second pawl, said cam-plate having an edge to ride against said arm when said plate is moved upwardly and withdraw said second pawl from said toothed bar and to recede from said arm when moved downwardly and thereby permit said second pawl to engage said bar and support the load until the first 10 pawl is again moved upwardly and has engaged said bar, and a setting lever for controlling the action of said spring on said cam-plate.
3. A jack comprising a casing and base, a 25 vertical toothed bar mounted in said casing to support the load, an actuating hand lever pivotally mounted at its inner portion between the sides of said casing, a pawl having a pin on its side and pivotally mounted 30 on the inner end of said actuating lever and operable therefrom and adapted to engage said bar, and a second pawl pivotally mounted between said sides and adapted to engage said bar while the other or first pawl is disengaged operatively therefrom, said second 35 pawl having a projecting arm, combined with a cam-plate pivotally mounted adjacent to the side of said first pawl and having an upper portion to engage said arm and a lower angular portion containing an opening receiving said pin on said first pawl, a 40 spring engaging said cam-plate and acting to turn the upper portion of said plate outwardly against said arm of said second pawl, said cam-plate having an edge to ride against said arm when said plate is moved upwardly and withdraw said second pawl from said toothed bar and to recede from said arm when moved downwardly and thereby permit 45 said second pawl to engage said bar and support the load until the first pawl is again moved upwardly and has engaged said bar, and means operable from without said casing for releasing said bar to drop.
4. A jack comprising a casing and base, a 50 vertical toothed bar mounted in said casing to support the load, an actuating hand lever pivotally mounted at its inner portion between the sides of said casing, a pawl having a pin on its side and pivotally mounted 55 on the inner end of said actuating lever and operable therefrom and adapted to engage said bar, and a second pawl pivotally mounted between said sides and adapted to engage said bar while the other or first pawl 60 is disengaged operatively therefrom, said second pawl having a projecting arm, combined with a cam-plate pivotally mounted adjacent to the side of said first pawl and having an upper portion to engage said arm and a lower angular portion containing an opening receiving said pin on said first pawl, a 65 spring engaging said cam-plate and acting to turn the upper portion of said plate outwardly against said arm of said second pawl, said cam-plate having an edge to ride against said arm when said plate is moved upwardly and withdraw said second pawl from said toothed bar and to recede from said arm when moved downwardly and thereby permit said second pawl to engage said bar and support the load until the first pawl is again moved upwardly and has engaged said bar, and means operable from without said casing for releasing said bar to drop.
5. A jack comprising a casing and base, a 70 vertical toothed bar mounted in said casing to support the load, an actuating hand lever pivotally mounted at its inner portion between the sides of said casing, a main pawl having an upper portion to engage said arm and a lower angular portion containing an opening receiving said pin on said first pawl, a 75 spring engaging said cam-plate and acting to turn the upper portion of said plate outwardly against said arm of said second pawl, said cam-plate having an edge to ride against said arm when said plate is moved upwardly and withdraw said second pawl from said toothed bar and to recede from said arm when moved downwardly and thereby permit said second pawl to engage said bar and support the load until the first pawl is again moved upwardly and has engaged said bar, an arm extending downwardly from said first pawl, and a movable 80 frame within said casing in near relation to said downwardly extending arm and having an exposed portion to be subjected to pressure when said frame is to be forced against said arm for effecting the release of said bar to drop.
5. A jack comprising a casing and base, a 85 vertical toothed bar mounted in said casing for supporting the load, an actuating hand lever pivotally mounted at its inner portion between the sides of said casing, a main pawl pivotally mounted on the inner end of said actuating lever and operable therefrom and adapted to engage said bar, a second pawl pivotally mounted between 90 said sides and adapted to engage said bar while the main pawl is disengaged operatively therefrom, a plate pivotally mounted adjacent to the side of said main pawl so as to move therewith and having an edge in engagement with said second pawl, and a spring engaging said plate and acting to turn the same against said second pawl, said edge being a cam to ride against said second pawl when said plate is moved upwardly and withdraw said second pawl from said toothed bar and to recede from said pawl when said plate is moved downwardly and thereby permit said second pawl to engage said bar and support the load until the main pawl is again moved upwardly and has engaged said bar, whereby on the oscillatory movement of the actuating lever the lifting bar becomes lowered.
6. A jack comprising a casing and base, a 100 vertical toothed bar mounted in said casing for supporting the load, an actuating hand lever pivotally mounted at its inner portion between the sides of said casing, a main pawl pivotally mounted on the inner end of said actuating lever and operable therefrom and adapted to engage said bar, a second pawl pivotally mounted between 105 said sides and adapted to engage said bar while the main pawl is disengaged operatively therefrom, a 110 actuating lever pivotally mounted at its inner portion between the sides of said casing, a main pawl pivotally mounted on the inner end of said actuating lever and operable therefrom and adapted to engage said bar, a second pawl pivotally mounted between said sides and adapted to engage said bar while the main pawl is disengaged operatively therefrom, a 115 actuating lever pivotally mounted at its inner portion between the sides of said casing, a main pawl pivotally mounted on the inner end of said actuating lever and operable therefrom and adapted to engage said bar, a second pawl pivotally mounted between said sides and adapted to engage said bar while the main pawl is disengaged operatively therefrom, a 120 actuating lever pivotally mounted at its inner portion between the sides of said casing, a main pawl pivotally mounted on the inner end of said actuating lever and operable therefrom and adapted to engage said bar, a second pawl pivotally mounted between said sides and adapted to engage said bar while the main pawl is disengaged operatively therefrom, a 125 actuating lever pivotally mounted at its inner portion between the sides of said casing, a main pawl pivotally mounted on the inner end of said actuating lever and operable therefrom and adapted to engage said bar, a second pawl pivotally mounted between said sides and adapted to engage said bar while the main pawl is disengaged operatively therefrom, a 130 actuating lever pivotally mounted at its inner portion between the sides of said casing, a main pawl pivotally mounted on the inner end of said actuating lever and operable therefrom and adapted to engage said bar, a second pawl pivotally mounted between said sides and adapted to engage said bar while the main pawl is disengaged operatively therefrom, a

- plate pivotally mounted adjacent to the side of said main pawl so as to move therewith and having an edge in engagement with said second pawl, and a spring engaging said 5 plate and acting to turn the same against said second pawl, said edge being a cam to ride against said second pawl when said plate is moved upwardly and withdraw said second pawl from said toothed bar and to 10 recede from said pawl when said plate is moved downwardly and thereby permit said second pawl to engage said bar and support the load until the main pawl is again moved upwardly and has engaged said bar, 15 whereby on the oscillatory movement of the actuating lever the lifting bar becomes lowered, combined with a manually operative setting-lever for controlling the action of said spring on said cam-plate.
- 20 7. A jack comprising a casing and base, a vertical toothed bar mounted in said casing for supporting the load, an actuating hand lever pivotally mounted at its inner portion between the sides of said casing, a 25 main pawl pivotally mounted on the inner end of said actuating lever and operable therefrom and adapted to engage said bar, a second pawl pivotally mounted between said sides and adapted to engage said bar 30 while the main pawl is disengaged operatively therefrom, a plate pivotally mounted adjacent to the side of said main pawl so as to move therewith and having an edge in engagement with said second pawl, and 35 a spring engaging said plate and acting to turn the same against said second pawl, said edge being a cam to ride against said second pawl when said plate is moved upwardly and withdraw said second pawl from said 40 toothed bar and to recede from said pawl when said plate is moved downwardly and thereby permit said second pawl to engage said bar and support the load until the main pawl is again moved upwardly and has engaged said bar, whereby on the oscillatory 45 movement of the actuating lever the lifting bar becomes lowered, combined with means operable from without said casing for releasing said bar to drop.
8. A jack comprising a casing and base, a vertical toothed bar mounted in said casing for supporting the load, an actuating hand lever pivotally mounted at its inner portion between the sides of said casing, a main pawl pivotally mounted on the inner end of said actuating lever and operable therefrom and adapted to engage said bar, a second pawl pivotally mounted between said sides and adapted to engage said bar while the main pawl is disengaged operatively therefrom, a plate pivotally mounted adjacent to the side of said main pawl so as to move therewith and having an edge in engagement with said second pawl, and a spring engaging said plate and acting to turn the same against said second pawl, said edge being a cam to ride against said second pawl when said plate is moved upwardly and withdraw said second pawl from said toothed bar and to recede from said pawl when said plate is moved downwardly and thereby permit said second pawl to engage said bar and support the load until the main pawl is again moved upwardly and has engaged said bar, whereby on the oscillatory movement of the actuating lever the lifting bar becomes lowered, combined with an arm connected with said main pawl, and a movable frame within said casing and having an exposed portion to be subjected to pressure for moving said frame against said pawl-arm to thereby release said bar to drop.
